Patented Oct. 27, 1959

186,450

COMBINATION PLAYING CARD AND SCORECARD HOLDER

Patrick A. Manning, Chicago, Ill.

Application March 6, 1959, Serial No. 54,882

Term of patent 7 years

(Cl. D34—5)

FIG. 1

FIG. 2

FIG. 3

FIG. 4

FIG. 5

Fig. 1 is a front elevational view of a combination playing card and scorecard holder embodying my new design;

Fig. 2 is a side elevational view thereof as seen from the right hand side of Fig. 1;

Fig. 3 is a top plan view of the same;

Fig. 4 is a rear elevational view thereof; and

Fig. 5 is a perspective view of the same.

I claim:

The ornamental design for a combination playing card and scorecard holder, substantially as shown.
